ATTORNEY

PHOTOGRAPH HOLDER MEANS

BACKGROUND OF THE INVENTION

The present invention pertains to receptacles for use with prints produced by cameras wherein the exposed print is developed immediately after its exposure within the camera and which thereafter requires the application of a protective coating.

There are print holders on the market today for holding and/or retaining a print to facilitate the application of a protective coating thereon. However, the present invention with its unique combination of features overcomes problems that are inherent in present day containers or holders. As is well known in the art of photography, a photograph made by way of the above type of cameras must be given a coating sometime after its development. This coating upon drying protects the picture from abuse by the elements and subsequent handling by people. Immediately after having coated such a photograph, it is quite troublesome to a photographer to hold the picture and coat it as well as place it in some suitable location where it can dry without hindrance. Care must be taken that the photograph is not allowed to come into contact with another object, especially other photographs, since the coating is adhesive in nature and thus will tend to stick to the object. By virtue of the present invention, these problems are simply and efficiently overcome in that novel container means are provided for facilitating the coating of prints and thereafter for inserting the prints in a fixed spaced apart relationship thereby preventing their contact. This and other advantages of the present invention will come to light as the discussion proceeds.

SUMMARY

The present invention basically provides photograph holder means which comprises container means having at least one open end. The container means is further defined in that one pair of its opposite interior sides are provided with multiple slotted portions extending lengthwise of the interior side taken with respect to an open end of the container. The slotted portions in turn are adapted for receiving a photograph inserted therein. In such manner, the photographs are retained in a spaced apart relationship thereby preventing their contact subsequent to drying.

The container means is further defined as including certain cutout portions to facilitate the removal of photographs therefrom. Additionally, it includes means for suspending the container upon the person of the user and for holding a print in place so that it can be readily coated.

DESCRIPTION OF THE DRAWING

FIG. 1 in the drawing shows a plan view of the present photograph holder means.

FIG. 2 depicts a view taken along the section line B-B of FIG. 1 showing a cross section of the present photograph holder means.

FIG. 3 represents a view taken along the section line A-A of FIG. 1 showing the internal slotted portions for retaining prints.

DESCRIPTION OF THE PREFERRED EMBODIMENT

The present invention basically comprises the container means 10 as shown in plan view in FIG. 1. The container means 10 is provided with at least one open end as shown in cross section in FIG. 2 so as to allow photographs after coating to be inserted therein.

A pair of the opposite sides of the container 10, viz. the sides 11 and 12, are provided with the slotted portions 13 and 14 respectively. The slotted portions, as shown in greater detail in FIG. 3, each comprise a multitude of the elongated slide members or guides 15 which run lengthwise along the interior of a given side. Each of the members 15 is provided with the rounded portion 16 at its end terminating at the open end

5 of the container 10. The rounded portions 16 of the various members 15 provide for the rapid insertion of a picture within a respective groove as formed between adjacent members 15. The ends 17 of the end guards 18 are tapered only on one side as shown in FIG. 3. The individual guard members 15 are of a lateral width sufficient to support a picture along its edge or border without contacting the picture itself. This prevents any marring of the picture in the event that it was to drag along a given slide member 15.

10 The slotted sides of the member 10 are provided with the cutout portions 20 and 21 respectively. As can be appreciated from FIG. 1, the edges of a picture fully inserted within the container 10 will be exposed by virtue of the indented or cut-out sections 20 and 21. The purpose of this is to allow the user to easily and rapidly retrieve a photograph from the holder 10. This is accomplished by placing, for example, the thumb and forefinger of the user on the edges of a picture contained in the member 10 whereby the picture can be slid outwards thereof. Of course, this feature also facilitates sliding a picture into the container 10. The indented portions 20 and 21 can also be positioned anywhere along the sides of the container 10. However, it is preferred to locate them rearwardly as shown in the drawing.

15 25 The container 10 is preferably provided with the clip 22 whereby prints undergoing development can be retained thus allowing the user to attend to other matters.

20 The container 10 is also provided with the slotted members 23 and 24 which are constructed to receive suspension means, e.g., a belt or a string, whereby the present holder can be suspended about the person of the user.

25 30 The ribbed or upraised portion 19 is provided for holding a print in place while it is being coated. That is, it prevents the print from sliding while the print coater is being passed back and forth over the print.

35 40 45 It can be appreciated that the present photograph holder can be fabricated of diverse materials of construction as well as being manufactured in innumerable ways. For example, the individual components can be fabricated separately and thereafter assembled in some suitable fashion. However, it is preferred that the entire structure be molded in a single unified structure. Moreover, it will also be apparent to one skilled in the art that many incidental changes can be made in the specific design of the present photograph holder without departing from the true scope and spirit of the instant invention.

I claim:

1. Photograph holder means comprising:
- 50 a. rectangular shaped container means having one end open; said container means being further defined in that one pair of its opposite sides are each provided with a cut-out portion in the proximity of its closed end whereby a photograph can be ejected from within said container means; said container means also being further defined in that one of its sides lying in a plane parallel with that established by a photograph when inserted within said container means is provided with raised portions extended entirely around its outer perimeter so as to provide an indentation wherein a photograph can be placed and thus prevent it from moving laterally while undergoing coating;
- b. guide means positioned lengthwise along the interior surfaces of said opposite sides of said container means (a) and provided with cutout portions congruent with the cut-out portions in the sides, said guide means extending longitudinally from the closed end of said container means (a) to its open end and positioned in a fixed spaced apart relationship so as to define a multitude of slots having a width sufficient to accommodate photographic paper; said guide means being further defined in that its ends adjacent the open end of said container means (a) are rounded whereby a photograph can be readily inserted within a respective pair of opposite slots;

- c. clip retaining means operably attached to one side of said container means (a) for retaining undeveloped photographs; and
- d. slotted means attached to opposite sides of said container

means (a), said means being adapted for receiving means for suspending said container means (a) on the person of the user.
